WRITING INSTRUMENT

Helmuth Riepe and Hermann Fritz Kaiser, Hamburg,
Germany, assignors to L. & C. Hardtmuth, Inc.,
Bloomsbury, N.J., a corporation of New Jersey

Filed Sept. 22, 1960, Ser. No. 62,234

Term of patent 14 years

(Cl. D74—17)

Fig. 1 is an exploded elevational view of a writing instrument showing our new design which comprises a combined nib and ink holding cartridge together with a cap to cover the nib;

Fig. 2 is an enlarged vertical cross section taken along the lines 2—2 of Fig. 1;

Fig. 3 is an enlarged horizontal cross section taken along lines 3—3 of Fig. 2; and

Fig. 4 is an enlarged elevational view of the cap portion shown partially in cross section.

This application is a continuation-in-part of our application Serial No. D. 53,415, filed November 18, 1958.

We claim:
The ornamental design for a writing instrument, substantially as shown and described.
